UNITED STATES PATENT OFFICE.

FRANK J. SCHUSTER, OF THERESA, WISCONSIN.

BUILDING BLOCK AND WALL.

941,656.

Specification of Letters Patent. Patented Nov. 30, 1909.

Application filed March 12, 1908. Serial No. 420,590.

To all whom it may concern:

Be it known that I, FRANK J. SCHUSTER, a citizen of the United States, residing at Theresa, county of Dodge, and State of Wisconsin, have invented new and useful Improvements in Building Blocks and Walls, of which the following is a specification.

My invention relates to improvements in artificial building blocks and walls.

The object of my invention is to provide a form of block which will readily lend itself to the construction of walls having single, double or triple air spaces extending horizontally in the wall and in which the air spaces when in double or triple vertical series will overlap so that any horizontal plane through the wall will cut one or more of such spaces.

A further object of my invention is to provide a block of the above described character, in which the air spaces in the walls will be formed partially in one block and partially in an adjacent block, so that a connecting web between the front and rear faces of the block may be provided at an intermediate point, as distinguished from those blocks in which connecting webs or members are located at the respective ends of the block.

In the following description reference is had to the accompanying drawings, in which,—

Figure 1 is a perspective view of a portion of one of my improved building blocks. Fig. 2 is an end view of a portion of a wall constructed from the blocks shown in Fig. 1 and having a single vertical series of air spaces. Fig. 3 is a similar view showing a wall having two vertical series of air spaces. Fig. 4 shows a wall composed of like blocks together with a special form of connecting block, whereby three vertical series of air spaces are secured. Fig. 5 is a view similar to Fig. 2 but showing blocks having flanges 3 and 4 of unequal lengths.

Like parts are identified by the same reference characters throughout the several views.

Referring to Fig. 1 it will be observed that my improved block is essentially chair-shaped, the same having an intermediate horizontal portion 1 from which a vertical flange 2 extends in one direction and two vertical flanges 3 and 4 (preferably of one-half the height of the flange 2) extending in

the opposite direction. The end of the member 1, together with the flanges 2 and 3, form one outer face of the block, while the opposing end of the member 1, taken with the flange 4, constitutes the other face of the block, a channel 5 being formed between the flanges 3 and 4.

To form the wall shown in Fig. 2, the blocks are laid up as illustrated in said figure, each alternate block being inverted, thus forming horizontally extending air spaces 6 between the flanges 2, 2, of superposed blocks and also forming air spaces 7 between the abutting flanges 3, 3, and 4, 4, of superposed blocks, the channels 5 in each block registering with each other to form the horizontally extending air space 7.

It will be observed that in Fig. 2, the blocks are directly superposed in a vertical column. In Fig. 3, however, each alternate block is offset and all the blocks are turned in the same direction. The flanges 3 and 4 of each extend upwardly (or downwardly as the case may be), but reversed end to end so that the flanges 2 and 3 of one block occupy a position in the front face of the wall and the flanges 2 and 3 of the next block occupy a position in the rear face of the wall, the flanges 4 of all the blocks being directly superposed in a vertical column in the central portion of the wall. This construction forms horizontally extending air spaces 8, composed in part of the channels 5 and in part of the spaces between the flanges 2 of one block and the flanges 4 of the next, or offset block.

Referring to Fig. 4 it will be observed that a wall is formed by arranging the blocks in two vertical columns, separated from each other at a width which is preferably equal to that of the channels 5 and arranged with the blocks of one column reversed in position end to end as compared with the opposing block of the adjacent column, the flanges 2 and 3 of all the blocks in one column being located in the outer face of the wall and the flanges 2 and 3 of all the blocks in the other column being located in the inner face of the wall. With this construction an auxiliary block 10 is employed to connect the opposing blocks in the respective columns, this auxiliary block being substantially rectangular in cross section, with the channel 5^a formed in one face thereof in a position to register with the space 9 between the columns, the channels 5^a

and the spaces 9 forming a horizontally extending air space which laps past the air spaces 11 formed by the channels 5 in the blocks of the respective columns and between the flanges 2 of those blocks and the front and rear side walls of the blocks 10. It will thus be observed that the form of block illustrated lends itself readily to the construction of building walls of any desired thickness or with any desired number of horizontally extending air spaces.

In Figs. 2, 3, and 4, the flanges 2 are all of the same length and the same is true of the flanges 3 and also of the flanges 4 of the several blocks illustrated. This feature, however, is not material to my invention since it is obvious that where it is desired to break joints, blocks may be made with flanges of unequal length as illustrated, for example, in Fig. 5, which shows each of the blocks provided with a shortened flange 3 and the flanges 4 correspondingly lengthened.

It will be observed that the interior meeting corners of the blocks are provided with beveled edges *a*, which form with the adjacent blocks, mortar receiving grooves, thus facilitating laying the blocks, as it is not necessary to interpose mortar between the ends of the blocks, the mortar being employed only in the grooves except along surface joints.

Having thus described my invention what I claim as new and desire to secure by Letters Patent is,—

1. An artificial building block, comprising a horizontally extending portion equal in width to the width of the block and having two side flanges extending in one direction and one side flange extending in the other direction, said last mentioned flange and one of the two flanges having their outer surfaces in the same plane with one side margin of the horizontal portion and forming the outer surface of the block.

2. An artificial building block, comprising

a horizontally extending portion equal in width to the width of the block and having at one margin upwardly and downwardly extending flanges having their outer surfaces in the same plane as the margin of the block, one of said flanges being twice the length of the other and said horizontally extending portion having at the other margin a projecting flange on the same side and parallel with the shorter of the two first mentioned flanges.

3. A building wall composed of a series of chair-shaped blocks, each having an intermediate portion provided with a single flange extending in one direction, and two parallel flanges extending in the other direction and arranged in the wall to form a series of horizontally extending air spaces between the flanges.

4. A building wall composed of a series of chair-shaped blocks, each having an intermediate portion provided with a single flange extending in one direction, and two parallel flanges extending in the other direction and arranged in the wall to form a series of horizontally extending air spaces between the flanges, some of said blocks being offset from the others and arranged to interlock therewith.

5. A building wall composed of a series of chair-shaped blocks, each having an intermediate portion provided with a single flange extending in one direction and two parallel flanges extending in the other direction, and arranged in the wall to form a series of horizontally extending air spaces between the flanges, together with an intermediate connecting block adapted to interlock with adjacent columns of the first mentioned blocks.

In testimony whereof I affix my signature in the presence of two witnesses.

FRANK J. SCHUSTER.
